E. F. HATHAWAY

TUBE FRAME

Filed April 10, 1923

Inventor:
T. T. Hathaway,
by
Geo. N. Goddard, atty.

UNITED STATES PATENT OFFICE.

EDGAR F. HATHAWAY, OF WELLESLEY, MASSACHUSETTS, ASSIGNOR TO SHAWMUT ENGINEERING COMPANY, OF BOSTON, MASSACHUSETTS, A CORPORATION OF MASSACHUSETTS.

TUBE FRAME.

Application filed April 10, 1923. Serial No. 631,226.

To all whom it may concern:

Be it known that I, EDGAR F. HATHAWAY, a citizen of the United States, and resident of Wellesley, in the county of Norfolk and 5 State of Massachusetts, have invented certain new and useful Improvements in Tube Frames, of which the following is a specification.

This invention relates to tube frame construction, and is intended to provide a simple, cheap and positively reliable supporting frame of very rigid construction for carrying the tuft tubes and the yarn spool for use in weaving tufted fabrics such as Ax- 10 minster carpets.

The strains to which the spool and tube-supporting frames are subjected in their travel to and from the loom has resulted in loosening the connections between the suspension hangers and the carrier bar, thus 20 impairing the reliability of its action and necessitating frequent replacement or repairs.

The present invention is founded upon 25 the principle of so constructing the tubular carrier bar which forms the backbone of the tube frame that it is provided with integral attaching wings so disposed and arranged as to afford a very rigid connection with the 30 suspension hangers by which the bar and the yarn-spool are suspended or supported from the usual conveyor chains. To this end the invention comprises, generally speaking, a tubular carrier bar whose ends 35 are formed with lateral or transverse integral wings adapted to lie or abut against the adjacent faces of the suspension arms or hangers and to be rigidly and firmly secured thereto preferably by detachable fastening 40 means. This and other features of the invention will be particularly explained in the following specification and will be defined in the claims hereto annexed.

In the accompanying drawings I have 45 illustrated several specific forms embodying the principles of this invention, in which:

Figure 1 is a front elevation, the end portion of a tube-frame embodying one form of the invention.

Figure 2 is a cross section through the carrier bar showing the lower portion of the hanger attached thereto.

Figure 3 is a detail showing in perspective the end of the carrier bar.

Figures 4 and 5 are details showing a 55 modified construction of carrier bar and hanger in front elevation and cross section, respectively.

Figure 6 is a front elevation showing another modification. 60

Figure 7 is a perspective view showing the end of the carrier bar illustrated in Figure 6.

Figure 8 is a front elevation of another modification. 65

Figure 9 shows a perspective of the end of the carrier bar, shown in Figure 8.

In the practice of this invention, according to the form illustrated in Figures 1 to 70 3, the main body portion 1, of the carrier bar is of tubular construction, polygonal in cross section, and has its top and bottom walls formed with transversely bent wings 10, extending at substantially right angles to the longitudinal axis of the carrier bar so as to expose flat outside faces against the inside face of the suspension hanger 2. The suspension hanger 2 as actually shown in this case is made of two laminated members 75 soldered or welded face to face having an upward chain engaging extension 3, and a bearing ear 4 which receives a journal of the yarn spool 6. Any suitable form of spring latch 5, may be secured to the outer face of the suspension hanger 2 so as to co-operate with the chain-engaging member 3 80 in the usual manner. 85

As the external faces of the attaching wings or members 10 lie in parallelism with the inside faces of the hangers it will be 90 seen that these parts can rest solidly against each other and may be attached together by any suitable means, preferably by attaching screws 11 which permits their disassembling when desired. 95

In Figures 4 and 5 I have shown a modified construction in which the suspension hanger 2 is provided with an angularly bent arm 2^a, which fits into a depression or countersunk recess formed in the end of the bottom wall of the tubular carrier bar 1, and which is rigidly but detachably united therewith by an attaching screw. An attaching wing 10 extending transversely from the top wall of the tubular bar forms a companion 100 attaching member, and there are also provided attaching wings 12 which are inturned from the opposite side walls of the carrier 105

bar to form additional attaching members extending at right angles to the attaching member 2^a, and the wing 10.

In the form shown in Figures 6 and 7 the hanger 2 is secured to the carrier bar 1, by means of integral attaching members 12 formed on the ends of the side walls of the carrier bar 1 to rest against the flat inside face of the suspension hanger, similar to the wings 12 of Figure 4 but in this case the top and bottom attaching members are omitted.

In Figures 8 and 9 are shown top and bottom attaching members 10 formed on the top and bottom walls of the carrier bar as previously described, but in this case the side walls are provided with perforated extensions or wings 14 which project endwise sufficiently to overlap the opposite side edges of the interposed suspension hanger 2, and are then bent transversely of the longitudinal axis of the bar to form external overlapping ears through which attaching screws may be passed into the exterior face of the hanger.

What I claim is:

1. A tuft tube frame for weaving embracing in its construction a suspension hanger, a tubular carrier bar of polygonal cross section having the end portions of opposite walls turned at substantially right angles to the longitudinal axis of the bar to form attaching wings adapted to rest firmly against the adjacent face of the hanger to which they are securely united, substantially as described.

2. A tuft tube frame for weaving embracing in its construction suspension hangers, a tubular carrier bar having endwise extensions bent transversely of the carrier bar, so as to lie against the adjacent opposed

faces of the hangers, and means for firmly but detachably securing the hangers to such extensions of the carrier bar, substantially as described.

3. A tuft tube frame for weaving embracing a carrier bar of polygonal cross section formed with integral attaching members bent at right angles to the walls of the bar to partially close the open ends thereof and presenting flat surfaces adapted to lie in contact with the inside faces of suspension arms, and a pair of suspension arms laid against the exposed flat faces of said attaching members and rigidly secured thereto, substantially as described.

4. A tuft tube frame for weaving embracing in its construction a suspension hanger, a tubular carrier bar of polygonal cross section whose adjacent walls are formed with integral attaching wings at the end of the bar bent transversely thereof to lie in a plane parallel with the inside face of the suspension hanger, and means for detachably securing the attaching members against said inside faces of the hangers, substantially as described.

5. A tuft tube frame for weaving embracing in its construction, a suspension hanger, a tubular carrier bar of polygonal cross section having the end portion of its top and bottom walls bent to form integral transverse attaching wings and having its opposite side walls also bent to form attaching wings extending substantially at right angles to the first named attaching wings, and means for securing the wings against the face of the hanger against which they are disposed, substantially as described.

In witness whereof, I have subscribed the above specification.

EDGAR F. HATHAWAY.
